(57) **CLAIM**

The ornamental design for a portable blind, as shown and described.

DESCRIPTION

The present application hereby incorporates by reference the entire disclosure of United States patent application Ser. No. 29/610,627, filed Jul. 13, 2017.

FIG. 1 is an isometric view of a portable blind according to the present invention.

FIG. 2 is a front view of the portable blind.

FIG. 3 is a back view of the portable blind.

FIG. 4 is a left view of the portable blind.

FIG. 5 is a right view of the portable blind.

FIG. 6 is a top view of the portable blind; and,

FIG. 7 is a bottom view of the portable blind.

1 Claim, 7 Drawing Sheets
